(21) Appl. No.: **29/353,060**

(57) **CLAIM**

The ornamental design for a high definition multimedia interface connector with a cable overmold, as shown and described.

(22) Filed: **Dec. 31, 2009**

DESCRIPTION

(51) **LOC (9) Cl. 13-03**

FIG. 1 is a front perspective view of a high definition multimedia interface connector with a cable overmold, showing my new design;

(52) **U.S. Cl. D13/147**

FIG. 2 is a top plan view thereof;

(58) **Field of Classification Search** D13/133,

FIG. 3 is a bottom plan view thereof;

D13/146-147, 153, 154, 156, 184; 439/79,

FIG. 4 is a right side elevation view thereof, the left side elevation view being a mirror image thereto;

439/248, 258, 274, 350, 353, 358, 447, 476.1,

FIG. 5 is a front elevation view thereof; and,

439/607.01, 607.04, 607.05, 607.17, 607.25,

FIG. 6 is a rear elevation view thereof.

439/607.34, 607.41, 607.53, 660, 668, 680

The broken line portion of the figure drawings is included to show unclaimed subject matter only and forms no part of the claimed design.

See application file for complete search history.
